(57) **CLAIM**

The ornamental design for a camera recording device for use with a gun, as shown and described.

DESCRIPTION

FIG. 1 is a front perspective view of a camera recording device for use with a gun;

FIG. 2 is a rear perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof;

FIG. 8 is a rear elevation view thereof; and,

FIG. 9 is a reduced right side elevation view thereof, shown in use with a gun.

The broken lines in FIG. 9 depict a gun showing environment only, forming no part of the claimed design.
